UNITED STATES PATENT OFFICE.

MORRIS M. EINSON, OF YONKERS, NEW YORK, ASSIGNOR TO EINSON-FREEMAN CO., INC., A CORPORATION OF NEW YORK.

ADVERTISING DISPLAY DEVICE.

Application filed June 9, 1927. Serial No. 197,636.

This invention relates to advertising display devices and more particularly to display devices having a supporting frame and a plurality of display faces of unequal size; each 5 of which are so constructed to support one another at equal or unequal distances between them by means of supports cut from their center portions.

The object of my invention is to produce a 10 display device which can be readily shipped in a collapsed condition and which can be easily and quickly assembled for display purposes; said assembling causing a plurality of display faces of unequal sizes to be forced 15 forward from one another to give the device depth and beauty.

Another object of my invention is to produce a display device, the various parts of 20 which are rigidly held and prevented from collapsing by a single means cut in the rear wall of the supporting frame.

A further object of my invention is to produce a display device which will be attractive and appealing to the eye, and which will be 25 inexpensive to manufacture.

With these and other objects in view, to be more fully set forth hereinafter, the invention consists in the novel construction, combination of elements and arrangement of 30 parts which will be exemplified in the operation and construction herein described in the following specification and illustrated in the accompanying drawings.

The invention will first be described in connection with the accompanying drawings, 35 wherein similar reference characters are used to designate corresponding parts throughout the several views, and more specifically defined and indicated in the appended claims.

40 Attention is directed to the drawings in which:—

Fig. 1 is a front view of my improved display device;

Fig. 2 is a side view of same;

45 Fig. 3 is a plan view looking in the direction of the arrows on the line 3—3 of Fig. 2;

Fig. 4 is a rear view;

Fig. 5 is a rear view of my device when collapsed; and

50 Fig. 6 is a plan view of the device when near its full collapsed position.

Referring to the various figures of the drawings, the numeral 1 indicates a collapsible supporting frame composed of the rear 55 wall 2, the side walls 3 and 4, the bottom

edges of which are so cut to cause the device to lean backward to support the overhanging weight of the device, the flaps 5 and the locking tab 6 cut in the rear wall 2. The orifice 7 punched in the locking tab 6 is provided for 60 the purpose of more readily pulling said tab out of the locking position when the device is to be collapsed. Securely fastened to the flaps 5 is the display face 8 which has the supports 9 having the inwardly bent flaps 10 cut 65 from its center portion. The display face 11 is securely fastened to the flaps 10 of the supports 9 and it in turn has the supports 12 having the inwardly bent flaps 13 cut from its center portion, upon which is securely fas- 70 tened the front display face 14.

The locking tab 6 is so shaped to snugly fit between the walls 3 and 4 of the support and the inner surfaces of the supports 9 and 12 when it is bent inward as illustrated most 75 clearly in Figures 2 and 3; thus rigidly holding all the parts in their respective positions irrespective of the flaps 5, 10 and 13 having been sufficiently creased to cause their taking their proper positions. To unlock the tab 6, 80 a finger or some instrument such as a pencil is inserted in the orifice 7 to pry it upward until it is flush with the surface of the rear wall as illustrated in Fig. 5. The supporting frame and the display faces can then be 85 caused to come into contact with one another by means of a slight squeezing pressure which is readily seen by observing Fig. 6 which illustrates the device when nearing its full collapsed position, a view of which was not 90 drawn because it would not be clear and distinct upon reproduction and would only tend to complicate the drawings.

The number of the display faces may be increased or decreased to obtain the proper 95 advertising effectiveness of the device and their contours may be given any desired shape beside the circular form shown in the drawings to further beautify it. Should the number of display faces be increased, the width 100 of the side walls 3 and 4 of the supporting frame 1 must be increased or the included angle between the display face 8 and the bottom end of the walls 3 and 4 must be decreased so that the overhanging weight can 105 be balanced.

In accordance with the provisions of the patent statutes, I have described my invention, but I desire it understood that it is not confined to the particular form shown and 110

described, the same being merely illustrative, and that the invention can be carried out in other ways without departing from the spirit of my invention, and therefore, I claim broadly the right to employ all equivalent instrumentalities coming within the scope of the appended claims, and by means of which, objects of my invention are attained and new results accomplished as it is obvious that the 10 particular embodiments herein shown and described are only some of many that can be employed to attain these objects and accomplish these results.

Having now described my invention, what 15 I claim and desire to secure by Letters Patent, is:—

1. An advertising display device comprising a plurality of display faces having central cut-out portions, collapsible means 20 formed from said cut-out portions for supporting said faces, a collapsible support and a means forming part of said collapsible support for holding it and said display faces rigidly in position when on display.
2. In a device of the character described, 25 consisting of a display device having a plurality of display faces, each display face be-

ing provided with a collapsible support and a single means for holding said supports and display faces rigidly in open position when on display, said means engaging each of said faces.

3. A display device including a plurality of display faces and means for associating the same, each of said display faces having a central cut-out portion, means for supporting said device and a single member attached to said supporting means adapted to pass through said cut-out portions for holding said device rigidly in position when on display.

4. A display device consisting of a plurality of display faces each of said display faces having a central cut-out portion, said display faces being provided with supporting 45 means formed by the cut-out portions, means for supporting said device, said device supporting means including a member adapted to pass through said cut-out portions for engaging said device in rigid position while on display.

This specification signed this 7th day of June, 1927.

MORRIS M. EINSON.
